DESIGN FOR AN EMBLEM PIN OR THE LIKE

Ralph W. Crane, Detroit, Mich.

Application November 14, 1941, Serial No. 104,159

Term of patent 7 years

To all whom it may concern:

Be it known that I, Ralph W. Crane, a citizen of the United States of America, residing at 8132 Senator Street, Detroit, in the county of Wayne and State of Michigan, have invented a new, original, and ornamental Design for an Emblem Pin or the Like, of which the following is a specification, reference being had to the accompanying drawing, forming part thereof.

In the drawing

Fig. 1 is a front elevational view of an emblem pin, showing my new design; and

Fig. 2 is a top edge view thereof.

I claim:

The ornamental design for an emblem pin or the like, as shown.

RALPH W. CRANE.
